UNITED STATES PATENT OFFICE.

GEORGE SHAKESPEARE WILKINSON, OF LONDON, ENGLAND, AND MONTAGUE STANLEY NAPIER, OF CANNES, FRANCE, ASSIGNEES TO D. NAPIER & SON LIMITED, OF LONDON, ENGLAND, A BRITISH COMPANY.

INTERNAL-COMBUSTION ENGINE.

Application filed November 12, 1924. Serial No. 749,483.

To all whom it may concern:

Be it known that we, GEORGE SHAKESPEARE WILKINSON and MONTAGUE STANLEY NAPIER, both subjects of the King of England, and residing, respectively, at London, in England, and Cannes, Alpes Maritimes, in France, have invented certain new and useful Improvements in Internal-Combustion Engines, of which the following is a specification.

This invention relates to multicylinder internal combustion engines of the kind in which the cylinders radiate from the crank shaft and each cylinder or group of cylinders is provided at its head with one or more cam shafts, each cam shaft being driven by a radially disposed shaft. It is the object of the present invention to provide an arrangement of this general type in which the mechanism for driving the pumps for circulating oil and water and all such auxiliary appliances is improved and simplified and a compact general arrangement provided capable of being enclosed within a single casing.

To this end, according to this invention an oil circulating pump of the gear wheel type is driven directly from a radially disposed cam shaft driving shaft and the driven shaft of this pump in turn drives a water circulating pump and if desired also a rotary gas distributing valve for starting purposes. The gear wheel pump is preferably of the two stage type and in this case the water circulating pump may be driven from either one of the driven pump elements.

The arrangement is particularly, though not exclusively, applicable for internal combustion engines in which the cylinders radiate downwards from the crank shaft and the driving pinion for the pumps and like auxiliary devices is conveniently mounted upon the central radial shaft so that the pumps and other auxiliary apparatus driven therefrom are disposed approximately in the centre line of the engine and below the crank shaft.

A construction embodying the present invention is illustrated by way of example in the accompanying drawings in which,

Figure 1 is an end elevation of the engine partly in section,

Figure 2 is a central vertical sectional side

elevation showing the cam shaft driving gear and its casing,

Figure 3 is a central vertical section through the oil circulating pump on an enlarged scale, and

Figure 4 is a sectional elevation also on an enlarged scale showing the connection between the driven shaft of the oil circulating pump and the water circulating pump.

In the construction illustrated the engine is provided with a crank shaft A from which radiate three groups of cylinders B C D, the crank shaft being disposed above the cylinders. The crank shaft A carries at its end a bevel pinion A' which meshes with bevel pinions B' D' respectively carried by radial shafts B² D² which drive the cam shafts of their respective cylinder groups B and D in the known manner. The pinion D' carries a second pinion D³ which meshes with a bevel pinion C' on the shaft C², the pinions B' C' and D' thus overlapping in the usual way.

Formed upon the shaft C² towards its lower end is a pinion E which constitutes the driving pinion of a low pressure or scavenging oil circulating pump. This pump is formed within a casing F built into or forming part of the casing or cover which encloses the cam shaft driving mechanism generally. The pinion E not only acts as a driving member for the low pressure oil circulating pump, but further constitutes one of the elements of this pump which is of the known gear wheel type comprising three intermeshing gear wheels, E, E', E², and drives a high pressure pump or stage comprising intermeshing gear wheels G G' disposed above and upon the same shafts as the pinions E' E² respectively.

At its lower end the shaft H, upon which the pinions G' E² are mounted carries a bevel pinion H' which meshes with a similar pinion J on the shaft J' of a centrifugal water circulating pump J² of known construction.

Keyed to or formed integral with the high pressure pump pinion G, and above this pinion, is a driving pinion K meshing with a pinion K' on the shaft of a rotary valve used for starting purposes, by means of which air or gas under pressure is distributed to the various cylinders. The starting air or gas is distributed through ports K² radiating

from the casing of the valve, the pipes connecting the valves to the various cylinders being omitted from Figure 2 for the sake of clearness as the valve itself and these connections are of known construction.

It will thus be seen that a single pinion on the cam shaft driving shaft of the central group of cylinders serves to impart the necessary drive to the oil circulating pumps, to the water circulating pump and to the rotary starting valve and that all this auxiliary apparatus is enclosed in a suitable casing which can be readily detached from or with the casing enclosing the cam shaft driving mechanism of the central cylinder group.

It will be appreciated that the particular manner in which the central radial shaft is driven is immaterial and that the constructional details may be varied without departing from this invention.

What we claim as our invention and desire to secure by Letters Patent is:—

1. A multicylinder internal combustion engine having cylinders or groups of cylinders radiating from the crank shaft including in combination at least one cam shaft adjacent to each cylinder head, at least one radially disposed cam shaft driving shaft, a gear pump for circulating oil comprising a driving gear wheel carried by a radial cam shaft driving shaft and a driven gear wheel meshing therewith, a water circulating pump and means for driving the water circulating pump from the driven gear wheel of the oil circulating pump.

2. A multicylinder internal combustion engine having cylinders or groups of cylinders radiating from the crank shaft including in combination at least one cam shaft adjacent to each cylinder head, at least one radially disposed cam shaft driving shaft, a gear pump for circulating oil comprising a low pressure stage the driving gear wheel of which is mounted on a radially disposed cam shaft driving shaft and a high pressure stage driven from one of the driven gear wheels of the low pressure stage, a water circulating pump and means for driving the water circulating pump from one of the driven gear wheels of the oil circulating pump.

3. A multicylinder internal combustion engine having cylinders or groups of cylinders radiating from the crankshaft including in combination at least one cam shaft adjacent to each cylinder head, at least one radially disposed cam shaft driving shaft, a gear pump for circulating oil comprising a driving gear wheel carried by a radial cam shaft driving shaft and a driven gear wheel meshing therewith, a water circulating pump, a rotary gas distributing valve for starting purposes and means for driving the water circulating pump and the distributing valve from the driven gear wheel of the oil circulating pump.

4. A multicylinder internal combustion engine having groups of cylinders radiating from the crank shaft including in combination an overhead cam shaft for each group of cylinders, a radially disposed cam shaft driving shaft for each cam shaft, a gear pump for circulating oil comprising a driving gear wheel carried by one of the radial cam shaft driving shafts and a driven gear wheel meshing therewith, a water circulating pump, a rotary gas distributing valve for starting purposes and means for driving the water circulating pump and the distributing valve from the driven gear wheel of the oil circulating pump.

5. A multicylinder internal combustion engine having groups of cylinders radiating from the crank shaft including in combination an overhead cam shaft for each group of cylinders, a radially disposed driving shaft for each cam shaft, a gear pump for circulating oil comprising a low pressure stage the driving gear wheel of which is carried by one of the radial cam shaft driving shafts and a high pressure stage driven from one of the driven gear wheels of the low pressure stage, a water circulating pump, a rotary gas distributing valve and means for driving the water circulating pump and rotary distributing valve from one of the driven gear wheels of the oil circulating pump.

In testimony whereof we have signed our names to this specification.

GEORGE SHAKESPEARE WILKINSON.
MONTAGUE STANLEY NAPIER.
